J. W. MAHONEY,

FIREPLACE ANDIRONS AND SCREEN.

APPLICATION FILED FEB 3 1932

1,416,369.

Patented May 16, 1922.

UNITED STATES PATENT OFFICE.

JOHN W. MAHONEY, OF WATERBURY, CONNECTICUT.

FIREPLACE ANDIRONS AND SCREEN.

1,416,369.

Specification of Letters Patent. Patented May 16, 1922.

Application filed February 3, 1922. Serial No. 533,990.

To all whom it may concern:

Be it known that I, JOHN W. MAHONEY, a citizen of the United States, and a resident of Waterbury, county of New Haven, and 5 State of Connecticut, have invented certain new and useful Improvements in Fireplace Andirons and Screen, of which the following is a specification.

This invention relates to fire-place goods 10 and more particularly to an ornamental combination of andirons and screen.

One object of the invention is to produce a device of this character in which the ornamental standard of the andirons is located 15 outside of the screen.

Another object is to produce a device of the above character in which the ornamental standard of the andirons may be readily removed for cleaning and polishing without 20 disturbing the remainder of the andirons or screen.

A further object is to provide a screen having a section which may be opened to 25 permit easy access to the interior of the fire-place for adjusting the fuel on the andirons without shifting the screen.

A still further object is to provide a combination andirons and screen which will be simple, ornamental, cheap to manufacture, 30 and very efficient and durable in use.

With these and other objects in view, there has been illustrated in the accompanying drawing, one form in which the invention may be conveniently embodied in practice.

Fig. 1 represents a perspective view of a combination screen and andirons embodying the invention, with the parts arranged in 35 assembled position.

Fig. 2 is an end view of one of the front ornamental standards, shown detached from the horizontal fuel-supporting rod of the andirons.

Fig. 3 is a fragmentary perspective view 40 partly in section of one of the doors of the screen, showing the guide ways in which the door is adapted to slide.

Fig. 4 is a perspective view of the ornamental top frame detached from the 45 remainder of the screen.

Fig. 5 is a front view of the left-hand door of the screen, shown in detached position.

Fig. 6 is a sectional view of the door taken along the line 6—6 of Fig. 5.

Fig. 7 is a rear view of one of the front 55 supporting plates for the andiron rods, showing the nuts which secure said plate to the wire screen.

Fig. 8 is a sectional view taken through the center of the andiron plates, and showing a portion of the lower part of the screen.

Fig. 9 is a perspective view of one of the intermediate andiron supports.

Fig. 10 is a perspective view of one of the rear andiron supports.

In the usual fire-place installation in dwelling houses, it is customary to employ a pair of andirons, each of which comprises a horizontal rod having front and rear supports. In such andirons, the front support 70 usually has an ornamental upstanding arm for retaining the wood or other fuel in position. When using such types of andirons, it was also customary to employ a fender or screen in front of the andirons to prevent 75 sparks from flying out into the room. When such a screen was employed, the andirons were, of course, hidden from view; and in order to display the ornamental standards thereof, it was necessary to remove the 80 screen.

Another disadvantage of such a type of andirons was that the ornamental standards thereof were so close to the fire that they rapidly became coated with tarry matter, 85 soot, ashes, etc. In order to properly clean and polish said standards, which was frequently necessary, the andirons had to be removed from the fire-place, and it was difficult to prevent the scattering of dirt and 90 ashes out into the room.

With the present invention, the above and other disadvantages have been avoided. The ornamental portion of the andirons is located entirely outside the screen, so that 95 it will be fully visible at all times without removal of the screen. Moreover, as the ornamental standard is at the front of the fire-place away from fumes and smoke, it will be less readily tarnished or coated with 100 soot, smoke, ashes or tarry matters. Hence it will be unnecessary to clean or polish the ornamental portions of the andirons except at rare intervals. However, when it is desired to clean them, this may be readily done 105 without removing the screen or andirons from the fire-place.

Referring now to the drawing in which

like reference numerals denote corresponding parts throughout the several views, the screen comprises a frame work made up of four vertical strips 10, 10^a, joined at their 5 ends to the ends of two front horizontal strips 11, 11^a, a rear horizontal strip 11^b, and four horizontal side stiffeners 12, 12^a. In order to enclose the screen, each of the 10 four frames thus formed is provided with wire mesh sections 13, 14, 15, 15^a, joined to the sides of said frames in any suitable manner, as by riveting or soldering. The four vertical strips 10, 10^a, the top horizontal front strip 11^a, and the side horizontal strips 15 12^a are preferably made angular in cross-section, as shown.

To enhance the artistic appearance of the screen, the front and side frames are surmounted by a three-sided top piece 16 comprising a front section 16^a and side sections 16^b. These sections 16^a and 16^b preferably have curved top edges, and scalloped bottom edges, as most clearly shown in Figs. 1 and 4. The top piece is preferably secured to the vertical strips 10 and 10^a of the screen by riveting.

In order to facilitate lifting the screen whenever desired, a pair of U-shaped handles 17 are provided upon the sides of said 30 screen. As clearly shown in Fig. 1, these handles are pivoted to eyelets 18^a on cross strips 18 secured to the vertical strips 10 and 10^a in any suitable manner as by riveting.

35 In order to assist in holding the andirons in position, the front section 17 of the screen is perforated by a pair of holes 20. On either side of said holes 20, front and rear perforated plates 22 and 23 respectively are 40 provided, the perforations in said plates being in alignment with said holes. The plates 22 and 23 have enlarged curved sections 24 concentric with the perforations 24^a, 24^b, and are suitably secured to the screen sections as by means of the bolts 25 and nuts 26. The andiron rods 21, which are preferably of iron or other similar material, are also held by a pair of rear supporting members 27, each of which has a pair of legs 27^a 45 and a circular top portion 28 inclosing a concentric bearing 28^a fitted tightly on said rod.

The andiron rods 21 are also held by intermediate supporting members 29, which 55 are tightly fitted over said rods 21 and are spaced at any suitable distance from the rear supporting members 27. The intermediate supporting members 29 are provided with legs 29^a and have upstanding arms 29^b 60 which retain the wood or other fuel in proper position in the fire-place. The supporting members 27 and 29 are preferably made of cast-iron or cast-steel of rectangular section, as clearly shown in the drawing.

65 In both the rear and intermediate support-

ing members the under parts of the top portion are preferably flat as clearly shown in Figs. 10 and 11.

As is clearly shown in Fig. 1, each and-iron-rod 21 projects a short distance in front 70 of the screen through the supporting plates 22 and 23. Each rod has its forward end beveled on its vertical sides, as shown and is perforated with a vertical socket to form a pivot bearing for the vertical portion 30 of 75 the hook 31 suitably secured as by screw-threads to the rear of the ornamental front standard to be described hereinafter. This construction permits the ornamental stand- 80 ard to be swung to the right or to the left of its central position in order to produce a different ornamental appearance and to facilitate manipulation of the doors of the screen.

As clearly shown in Figs. 1 and 2, the 85 ornamental standard comprises a base 32 having a pair of legs 33 which rest upon the hearth or floor in front of the screen. Formed integral with the base 32 is a flat horizontal crosspiece 34 which forms a sup- 90 port for a plurality of vertical rods 35. These rods 35 are secured at their tops to the top bar 36. Surmounting the top bar 36, which preferably has a curved upper portion and a flat base, are a pair of spaced 95 ornamental balls 37 and 38. These balls 37 and 38, of which the lower (37) is prefer-ably of larger diameter than the upper 38, are rigidly connected by neck portions 39 and 40, the latter being secured to the top 100 bar 36.

It will be understood that various other ornamental standards may be substituted for the one illustrated, within the scope of the invention.

105 Doors 41 and 42 are slidably mounted in U-shaped guide ways 43 and 44, as clearly shown in Fig. 3, and preferably comprise a frame made up of four U-shaped strips 41^a, 41^b, and 41^b, 41^b, the screen portions 42^a 110 being soldered or otherwise united to the strips 41^a and 41^b. The guide ways 43 and 44 are secured in any suitable manner to the horizontal strips 43^a and 44^a, and to the vertical strips 45 and 46, as clearly shown 115 in Figs. 1 and 3.

In order to facilitate the opening of the doors 41 and 42, they are provided with handle members 47, which preferably have depending rings 48.

120 From the foregoing, it will be understood that the invention provides a simple but effective means of constructing a novel form of combined andirons and screen.

While there has been disclosed in this 125 specification one form in which the invention may be conveniently embodied, it is to be understood that this form is shown for the purpose of illustration only, and that the invention is not to be limited to the spe- 130

cific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

10 1. In a combination fire-place fixture, a pair of andirons, and a screen, the forward ends of said andirons extending through and supported by said screen.

15 2. In a combination fire-place fixture, a pair of andirons, and a screen, each of said andirons extending through and partly supported by said screen and having a detachable standard in front of said screen.

20 3. In a combination fire-place fixture, a pair of andirons, a screen of reticulated material having a pair of reinforced openings, said andirons extending through said openings, said screen comprising a substantially rectangular frame open at the bottom 25 and back and having an ornamental top-piece.

4. In a combination fire-place fixture, a pair of andirons, a screen, said andirons extending through said screen, means behind said screen for supporting said andirons, said screen comprising a substantially rectangular frame open at the bottom and back, and having an adjustable closure in the front thereof to permit arrangement of 35 the fuel in the fire-place.

5. In a combination fire-place fixture, a pair of self supported andirons, and a screen, said andirons extending through said screen, said screen comprising a substantially rectangular frame open at the bottom and rear, said screen having an adjustable door sliding in the front thereof, whereby the fuel in the fire-place may be arranged without removing the screen.

45 6. A fire-place screen comprising a front frame, two side frames and a top frame joined together at their edges, each of said frames having a wire protecting screen, handles secured to said side frames, said 50 front frame having an adjustable closure to enable the fuel to be arranged within the fire-place without removing the screen, and a three-sided ornamental device mounted upon the top of the front and side frames 55 of said fender.

7. A fire-place screen comprising the combination of a front screen section with two side screen sections and a top screen integrally secured together, said front screen 60 section having a pair of horizontal spaced

guides and having an adjustable closure therebetween, and a slidable screen section mounted to slide between said guides.

8. In a combination fire-place fixture, a screen comprising front, side, and top 65 screen sections joined together at their edges, said front screen section having a pair of horizontal aligned openings near the bottom thereof, a pair of andirons, each of which has a horizontal rod extending 70 through and supported by said screen, each of said horizontal rods being also provided with a rear support.

9. In a combination fire-place fixture, a screen comprising front, side, and top screen 75 sections joined together at their edges, said front screen section having a pair of horizontal aligned openings near the bottom thereof, a pair of andirons, each of which has a horizontal rod supported by and extending through said screen openings, each of said horizontal rods being also provided with a rear support and an intermediate support, said intermediate support having a vertical upstanding fuel-holding arm, and 80 an ornamental standard secured to each of said rods in front of said screen.

10. In a combination fire-place fixture, a pair of andirons, a screen comprising a front screen section, two side screen sections, and a top screen section, said side screen sections having handles secured thereto, said front screen section having adjustable doors to permit manipulation of the fuel on the fire and also having a perforated 95 frame adapted to form a support for the forward ends of a pair of andirons, an ornamental frame secured to the top of said fender and a pair of ornamental standards pivotally connected to the forward ends 100 of said andirons, said ornamental standards being adapted to be swung about their pivots to vary the ornamental effect.

11. In a fire-place fixture, a screen, a fuel-supporting device comprising a horizontal 105 rod whose front end is supported in said screen, said rod being also provided with a second support having an upstanding fuel-holding arm.

12. In a fire-place fixture, an andiron, 110 an ornamental standard comprising a vertical base member, an ornamental top member, and a rearwardly and downwardly extending hook secured to said base member, said hook adapted to be pivotally mounted 115 in a bearing in the front end of the andiron.

In testimony whereof, I have affixed my signature to this specification.

JOHN W. MAHONEY.
